UNITED STATES PATENT OFFICE.

FRANK KRZYSKO, OF AMSTERDAM, NEW YORK.

TUBE-RECTIFYING MACHINE.

1,234,183.

Specification of Letters Patent. Patented July 24, 1917.

Application filed January 5, 1917. Serial No. 140,716.

To all whom it may concern:

Be it known that I, FRANK KRZYSKO, a citizen of the United States, residing at Amsterdam, county of Montgomery, and State of New York, have invented certain new and useful Improvements in Tube-Rectifying Machines, of which the following is a specification.

Reference may be had to the accompanying drawing, and the reference characters marked thereon, which form a part of this specification. Similar characters refer to similar parts in the several figures therein.

In the weaving of Axminster fabrics, the strands of filling-yarn as they pass from the roll are led through a number of small tubes, whereby the yarns of different colors are guided and presented to the loom-mechanism in proper relative position for incorporation into the fabric.

These tubes are made of thin sheet-metal such as tin, and are mounted side by side upon a supporting-frame, from which the tubes project a considerable distance separately and unsupported.

The tubes suffer frequent injury in use and in transportation to and from the looms, and require to be constantly rectified or renewed in order to insure their proper operation.

The rectifying of such tubes has heretofore been done largely by hand, requiring the careful insertion of a punch through the several tubes to straighten them and restore them to proper cross-sectional form; but in rectifying tubes by hand as heretofore practised, the tubes have not been properly exteriorly supported to coöperate with the inserted punch, so that the results have been more or less crude.

In such attempts as have been made to rectify such tubes by machine the operation has been slow and tedious, permitting the operation of the machine upon only part of the tubes of the frame at one time, and depending largely upon the operator for the manual operation of the various devices to successively act upon the tubes.

The principal objects of the present invention are to facilitate the rectifying of such tubes; to rectify the tubes automatically without particular attention of the operator of the machine to the successive rectifying operations; to properly support the tubes during the operation of the machine;

to simultaneously rectify the tubes of an entire frame; and to secure a more uniform and perfect rectifying of the tubes.

Other objects will appear in connection with the following description.

Figure 1 of the drawings is a view in side elevation of a tube-rectifying machine embodying my invention.

Fig. 2 is a view in front elevation of the same.

Fig. 3 is a top plan view of the same partly broken away and with one of the tube-frames partly broken away shown in position in the machine.

Fig. 4 is a bottom plan view of one of the mandrels detached.

Fig. 5 is a side view of the same.

Fig. 6 is an edge view of a broken-away portion of the swaging-plate inverted.

Fig. 7 is a top plan view of a similar portion of the swaging-plate.

Fig. 8 is a cross-section of the same taken on the broken line 8—8 in Fig. 7.

Fig. 9 is a bottom plan view of a broken-away portion of the swaging-bar.

Fig. 10 is a top plan view of a broken-away portion of a tube-frame.

Fig. 11 is a vertical cross-section taken on a plane transverse to the tubes showing one of the tubes engaged on its inner side by a mandrel, on its upper side by the swaging-bar, and on its lower side by the swaging-plate.

Fig. 12 is a vertical section taken longitudinally through a part of the machine on the broken line 12—12 in Fig. 2.

Fig. 13 is a plan view of the cam-mechanism for locking the tube-frame in position.

Fig. 14 is a side view of the same.

Referring to the drawings wherein the invention is shown in preferred form, 1 is the frame of the machine, having supports, 2, for the opposite ends of a tube-frame, 3, having numerous tubes, 4, mounted thereupon. Abutments, 5, form stops against which the frame is forced by a plurality of cams, 6, pivotally mounted at 7, upon a frame, 8, in fixed relation to the frame of the machine.

The cams, 6, are simultaneously operated by means of a T-frame, 9, the head, 10, of which is pivotally connected at 11, with the respective arms, 12, on the cams.

The body of the T-frame, 9, is adapted to

be reciprocated laterally within a slideway, 13, by means of an operating-handle, 14, which handle extends along the front side of the machine, and is adapted to play longitudinally in slideways, 15, formed in the frame, 8.

A pair of diagonal links, 16, are pivotally connected at 80, together and to the body of the T-frame, 9, and at their other ends they 10 are pivotally connected to the respective cam-arms, 12, whereby said cams are operated in unison.

When the tube-frame is mounted in the machine, its tubes, 4, overlie and rest upon a swaging-plate, 17, which is adapted to reciprocate longitudinally along a path extending 15 transversely of the row of tubes, 4.

This swaging-plate is adapted to be reciprocated by means of a lever, 18, having its 20 upper end, 19, loosely fitting an aperture, 20, in one end of the swaging-plate, the other end of the swaging-plate being provided with a longitudinal guide-slot, 21, through which extends a guide-finger, 22, 25 fixed upon the frame of the machine.

The lever, 18, is pivoted at 23 upon the frame of the machine, and has upon its other end a cam-follower, 24, adapted to be engaged by a cam, 25, fixed upon a shaft, 26, 30 rotatively mounted in bearings upon the frame of the machine.

The shaft, 26, is operated through a train of gears, 27, 28, 29 and 30, from a clutch-driven shaft, 31, which has non-rotatively 35 mounted thereon, and slideable longitudinally thereof, one member, 32, of a clutch.

The complementary clutch-member, 33, is fixed upon a gear-wheel, 34, both being rotatively mounted upon the shaft, 31, with 40 said gear-wheel, 34, in engagement with a pinion, 35, fixed upon a main drive-shaft, 36, carrying a pulley, 37, adapted to receive a driving-belt, not shown.

The clutch-member, 32, is operated to engage 45 the clutch-member, 33, by means of an angle-lever, 38, fulcrumed at 39, upon the frame of the machine, the lower member of which angle-lever is engaged by an arm, 40, of a foot-operated lever, 41, fulcrumed at 50 42, upon the frame of the machine.

A series of mandrels, 43, is mounted upon a slide-carriage, 44, movable along slideways, 45, longitudinally of the machine parallel with the tubes, 4, with the mandrels in 55 line with the respective tube-openings when the tube-frame is properly placed in the machine.

The slide-carriage, 44, has on its upper side a longitudinal flange or rib, 75, formed 60 with grooved seats, 76, for the shanks of the respective mandrels, which shanks are notched at 77 on their under side to make interlocking engagement with the respective grooved seats, as shown in Fig. 12. The 65 shanks of the mandrels are held to their

seats in the flange, 75, by means of an overlying clamp-plate, 79, and clamp-bar, 78.

This slide-carriage, 44, is adapted to be reciprocated along the slideways, 45, by means of a pair of links, 46, pivotally connected at one end to the respective ends of said slide-carriage, 44, each of said links being pivotally connected at its other end at 78, with the upper end of a link, 47, the lower end of which link is pivotally connected at 49 with the frame of the machine.

A connecting-rod, 50, connects an intermediate portion of each link, 46, with a crank-disk, 51, said crank-disks being fixed upon the opposite ends of a shaft, 52, rotatively mounted in bearings on the frame of the machine, and upon which shaft, 52, is fixed the gear-wheel, 28.

A swaging-bar, 53, is rockingly mounted by means of trunnions, 54, upon and between 85 a pair of levers, 55, fulcrumed upon a shaft, 56, mounted in a pair of slide-bearing-blocks, 57, reciprocatory along respective slideways, 58, longitudinally of the machine.

Each of said levers, 55, is pivotally connected at 59 with the upper end of a link, 60, the lower end of which link is pivotally connected at 61 with the frame of the machine.

Each of the levers, 55, is connected by a connecting-rod, 62, with a crank-disk, 63, 95 said crank-disks being fixed upon the opposite ends of the shaft, 26.

The under surface of the swaging-bar, 53, is grooved or toothed, as shown at 66, to form a matrix for the respective tubes, 4, 100 complementary to the respective mandrels, 43.

The ends of the levers, 55, which carry the swaging-bar, 53, are at certain times supported in elevated position, as shown in Fig. 1, by means of a pair of bars, 67, each vertically reciprocatory in a slideway-bracket, 68, at the respective side of the machine, and each pivotally connected at its lower end with a crank-pin, 69, on a crank-disk, 64, 110 said crank-disks being fixed upon the opposite ends of a shaft, 65, rotatively mounted in bearings on the frame of the machine, and having fixed thereon a gear-wheel, 86, meshing with the gear-wheel, 27.

As the crank-disks, 64, are rotated, the bars, 67, are raised and lowered in their respective slideways, 68.

The upper end of each bar, 67, is forked, one branch thereof, 70, engaging the under side of the neighboring lever, 55, while its other branch, 71, is connected with the corresponding branch of the bar, 67, on the other side of the machine by means of a guide-plate, 72, which may have graduations 120 marked thereon, as shown in Fig. 3, to assist the operator in accurately locating the tube-frame, so that the tubes, 4, will be properly aligned with the respective mandrels, 43.

Coil-springs, 73, connecting the respec- 130

tive bars, 67, with the frame of the machine, tend to draw the upper ends of the bars forward to bring the plate, 72, closely adjacent to the ends of the tubes, 4.

5 The swaging-plate, 17, is slightly tapered in cross-section, as shown in Fig. 8, the thicker edge of said plate being adjacent to the outer ends of the tubes, 4, causing said plate to act more effectively upon said tubes 10 near their outer ends.

The thicker edge of the swaging-plate is also preferably made in the form of a series of teeth, 74, which are slightly beveled on the side which engages the tubes, causing them 15 to operate with a wedging action to swage the tubes into proper form.

The operation of the machine is as follows:

The tube-frame having been placed in the 20 machine in the position shown in Fig. 3, and clamped in such position by means of the cams, 6, the machine is started by pressing down upon the foot-lever, 41, causing the clutch-member, 32, to engage the clutch-member, 33, thus setting in operation the 25 several shafts, 26, 52, and 65. A rearward movement is thus imparted to the slide-carriage, 44, causing the mandrels, 43, to enter the respective tubes, 4, expanding to full 30 size any which may have been indented or bent inward, and approximately straightening any which may have been bent out of alinement. The tube-engaging portion of each mandrel, 43, is of the cross-sectional 35 form of the interior of a perfect tube.

As the mandrels approach the limit of their rearward movement through the tubes, the swaging-bar, 53, will have been carried 40 forward from the position shown by solid lines to that indicated by dotted lines in Fig. 1, which movement is the resultant of the forward movement of the slide-bearing-blocks, 57, and the lifting action of the arm, 70, of the bar, 67.

45 As the swaging-bar, 53, reaches its forward position the bars, 67, are carried downward by the crank-pins, 69, and the swaging-bar, 53, is permitted to descend into engagement with the upper sides of the tubes, 4, causing the convergent upper sides of the 50 respective tubes to be pressed into shape between the respective mandrels, 43, and the grooved portions, 66, of the swaging-bar, which acts as a complementary matrix to 55 the mandrels.

During the first part of the return movement of the slide-bar, 57, the swaging-bar, 53, is drawn rearward along the tubes, swaging them into proper form upon their 60 respective mandrels by a sliding or ironing action.

While the swaging-bar, 53, is in engagement with the tubes, it serves to hold them down upon the swaging-plate, 17, while the same 65 is slid longitudinally from one side to the

other of the machine by means of the lever, 18, which movement causes the bottoms of the tubes to be pressed between the swaging-plate, 17, and the bottoms of the respective mandrels, 43, while said swaging-plate is 70 moving in a direction to cause its beveled teeth, 74, to engage the bottoms of the tubes with a wedging action.

During the operation of the machine upon the tubes, each tube is supported on all sides 75 of its interior by one of the mandrels, 43, while all sides of its exterior are being operated upon by the swaging-plate, 17, and swaging-bar, 53, thus causing the tubes to be rectified not only as to alinement, but as 80 to cross-sectional form as well.

A coil-spring, 81, connecting the lower arm of the lever, 38, with the frame of the machine tends to disengage the clutch-member, 32, from the clutch-member, 33. 85

Fixed upon the shaft, 42, which forms the fulcrum for the lever, 41, is a rocker-arm, 82, carrying a cam-follower, 83, engageable with a cam, 84, fixed on the shaft, 31.

This cam, 84, is of general circular form 90 having a notch or recess at 85 to receive the cam-follower.

After the machine has been set in operation by depressing the foot-lever, 41, the foot 95 of the operator can be removed and the machine after completing the cycle of operations above described will be automatically stopped by disengagement of the clutch-members due to the action of the spring, 81, when the cam-follower, 83, enters the notch, 100 85, in the cam, 84.

What I claim as new and desire to secure by Letters Patent is—

1. In a machine of the class described and in combination, a support for a tube-frame; 105 a longitudinally reciprocatory swaging-plate extending transversely of the tubes on said frame along one outer side of the tubes; swaging mechanism engageable exteriorly with the other side of the tubes; mandrels 110 adapted to enter within the several tubes; and means for imparting longitudinal reciprocating movements to said swaging-plate.

2. In a machine of the class described and 115 in combination, means for supporting a tube-frame; means extending transversely of the tubes on said frame for exteriorly supporting the tubes on one side; swaging mechanism extending transversely of the 120 tubes engageable exteriorly with the other side of the tubes and reciprocating longitudinally of the tubes; and means for reciprocating said swaging mechanism relatively to the tubes and to said tube-supporting means.

3. In a machine of the class described and in combination, a support for a tube-frame; mandrels adapted to enter within the several tubes on said frame; a plurality of 130

- swaging-members one movable longitudinally of the tubes and another movable transversely of the tubes; and means for moving said swaging-members.
5. 4. In a machine of the class described and in combination, a support for a tube-frame; mandrels adapted to enter within the several tubes on said frame; and a longitudinally reciprocatory swaging-plate extending transversely along one side of said tubes, said swaging-plate being thicker along its edge adjacent to the outer ends of the tubes than along its opposite edge.
- 10 5. In a machine of the class described and in combination, a support for a tube-frame; mandrels adapted to enter within the several tubes on said frame; and a longitudinally reciprocatory swaging-plate extending transversely along one side of said tubes, said swaging-plate having a plurality of beveled teeth engageable wedgingly with the tubes.
- 15 6. In a machine of the class described and in combination, a support for a tube-frame; mandrels adapted to enter within the several tubes on said frame; and a longitudinally reciprocatory swaging-plate extending transversely along one side of said tubes, said swaging-plate being thicker along its edge adjacent to the outer ends of the tubes than along its opposite edge, and having along its thicker edge a plurality of beveled teeth engageable wedgingly with the tubes.
- 20 7. In a machine of the class described and in combination, a support for a tube-frame; mandrels adapted to enter within the several tubes on said frame; a swaging-bar extending transversely of the tubes and having a grooved face adapted to form a matrix for the several tubes; and means for moving said swaging-bar into and out of en-
- gagement with the tubes and longitudinally of the tubes.
8. In a machine of the class described and in combination, a support for a tube-frame; reciprocatory mandrels adapted to enter within the several tubes on the frame; a longitudinally reciprocatory swaging-plate extending transversely along one side of the tubes; a movable swaging-bar engageable with the other side of the tubes; a power-driven shaft; and operating connections between said shaft and said mandrels, swaging-plate and swaging-bar.
- 10 9. In a machine of the class described and in combination, a support for a tube-frame; reciprocatory mandrels adapted to enter within the respective tubes on said frame; a longitudinally reciprocatory swaging-plate extending transversely along one side of the tubes; a swaging-bar extending transversely of the tubes reciprocatory along the opposite side of the tubes longitudinally thereof; a power-driven shaft; and operating connections between said shaft and said mandrels and swaging-plate and swaging-bar.
- 15 10. In a machine of the class described and in combination, a support for a tube-frame; a swaging-bar rockably mounted upon an axis extending transversely of the tubes on said frame and reciprocatory longitudinally of said tubes; means for automatically reciprocating said swaging-bar longitudinally of the tubes and for automatically moving said swaging-bar into engagement with the tubes during its movement in one direction, and out of engagement with the tubes during its movement in the opposite direction.
- 20 In testimony whereof, I have hereunto set my hand this 23rd day of December, 1916.
- FRANK KRZYSKO.
